UNITED STATES PATENT OFFICE

2,514,163

LOAD-BREAK FUSE SWITCH

Ralph R. Pittman, North Little Rock, Ark.

Application April 12, 1948, Serial No. 20,480

1 Claim. (Cl. 200—114)

1

This invention relates generally to fuse switches adapted for connection to electrical circuits, and particularly to a fuse switch construction suitable for interrupting load current by appropriate manipulation, which in addition functions as a fuse operable upon predetermined excess current.

Among the objects of the invention may be noted the provision of means for manually causing operation of the fuse and interruption of normal load current when desired; the provision of a fuse switch which may be opened and closed as desired without operation of the fuse, together with the automatic overload protection inherent in a fused device. Other objects will be obvious or pointed out hereinafter.

The invention comprises the elements and combinations thereof, features of construction and arrangement of parts to be exemplified in the description to follow, and the scope of the invention will appear in the accompanying claim.

Fig. 1 of the drawing is a side elevational view of the device, shown partly in section; Fig. 2 is an end view of the switch. Similar reference characters indicate corresponding parts in the figures of the drawing.

Load-break switches are well known and widely used in electrical construction; fuse constructions are also common. However, in situations requiring both interruption of load current and interruption of overload current, one structure is often supplied for load breaking and another and separate structure for overload interruption in response to the fusing of a fusible element. The advantages of accomplishing both of these functions by means of a single, simple structure, from the standpoint of the lower cost of the apparatus in addition to the lower cost of mounting, are obvious.

The manner in which my invention meets the foregoing requirements will be clear from the following description.

Referring to the drawing, the insulator 10 has secured at its upper end the upper conducting contact member 13 and at its lower end the lower conducting contact member 14, to which are respectively attached the line terminal 11 and the load terminal 12. A fuse tube 15, of insulating material, spans the space between the upper end and lower contact members, the upper fuse tube contact 26 conductively engaging the upper contact member 13, and the lower fuse tube contact 27 conductively engaging the lower contact member 14.

The fuse link 16 extends through the fuse tube 15, and electrically connects the upper contact

2

member 13 to the lower contact member 14, through its engagement at the button-head end with the upper fuse tube contact 26, and through the engagement of its outwardly extending end with the downwardly biased fuse link extractor 18. Within the tube 15, and between the lower open end thereof and the top of the tube, the fuse link 16 is provided with a mechanically weakened fusible element 17, of such tensile strength that the fuse link will rupture at the element 17 when the fuse link is subjected to a predetermined tension.

The fuse tube 15 is mounted on the lower contact member 14 by the pivot 19, and is provided with an eye 20 for convenient opening and closing of the fuse switch by means of an insulated switch stick, in which operations the upper fuse tube contact 26 disengages the upper contact member 13 as the tube 15 is rotated on the pivot 19.

At the lower end of the tube 15 and on the lower fuse tube contact 27 is pivotally mounted, for rotation about the pivot 22, the fuse link rupturing lever 21. This lever includes the arms 24, 25 which straddle the fuse tube 15, and which are joined at their inwardly extending ends by the laterally extending fuse-extractor engaging portion 25, which is so positioned that it engages the fuse extractor 18 in its path of movement and urges the latter in the direction to tension the fuse link 16 when the fuse link rupturing lever 21 is urged in counterclockwise direction about the pivot 22.

Preferably the fuse link rupturing lever 21 extends outwardly and downwardly from the open end of the fuse tube 15, and is provided with a recess 23 for receiving an insulated switch stick to urge the lever 21 in the direction to rupture the fuse link 16. The dotted lines indicate the position of the parts immediately after the fuse link rupturing lever 21 has been urged to the position to rupture the fuse link, but before the link has been completely extracted from the open end of the fuse tube.

From the above description, it will be seen that the circuit from the line terminal 11 to the load terminal 12 may be opened in either of two ways as desired, one by pulling the fuse tube 15 to open position, in which event only air break circuit interruption is available, or alternately by tensioning the fuse link to rupture, in which event the much more effective expulsion fuse interrupting ability is utilized.

If the magnitude of the current is such that the arc cannot be interrupted by air-break, as

may be readily determined by trial, then the fuse link rupturing lever 21 may be employed. In so doing, it will be observed that the force applied to tension the link to rupture is in the direction to close the switch. This is a most important consideration from the standpoint of avoiding unwanted air-break interruption and in addition providing assurance that the switch is in the fully closed position before the blast attending expulsion action is initiated by rupture of the mechanically weakened section within the tube. It is in this respect that the recess 23 is provided, instead of an eye, at the outer end of the fuse link rupturing lever 21.

The end of the fuse link rupturing lever 21 which is intended to be manipulated to cause breakage of the fuse link preferably extends outwardly beyond the pivot 22 for a distance greater than that from the other end of the lever to the pivot, to facilitate breakage of the higher amperage fuse links which, to handle rated current, are inherently of relatively high tensile strength. In the absence of the mechanical advantage so provided, such large amperage links are extremely difficult to fracture.

It will be apparent that changes and modifications may be made in the specific embodiment of the invention here shown and described and it is intended that the description herein will be regarded as illustrative rather than limiting.

I claim, as my invention:

In a fuse switch having an open position and a closed position, a fuse tube open at the lower end and swingable in upward direction for movement from open to closed position, a fuse link within said fuse tube, and a pivotally mounted fuse link rupturing lever on said tube at the open end and arranged to withdraw said fuse link from the open end of said tube in response to a predetermined movement of said lever in said upward direction, said lever extending respectively inwardly and outwardly beyond said fuse tube, the inwardly extending portion moving downwardly when the outwardly extending portion moves upwardly whereby said fuse tube is held in closed position while the fuse link is withdrawn from the open end of said tube.
